UNITED STATES PATENT OFFICE

CHARLES F. BECK, OF PARK RIDGE, ILLINOIS

MAIL BOX

Application filed November 7, 1927. Serial No. 231,416.

This invention relates to mail boxes designed mainly for residences, apartments and the like to receive and contain delivered mail matter, and it has reference more particularly to mail boxes of this character which are provided with a translucent panel for the display of a house number thereon and means for illuminating the panel at night.

In the development of the present invention, the principal object has been to improve the legibility of the illuminated house number panel, which object I attain by a construction that affords a reflected and suffused light on the panel rather than direct light rays thereon, and occupies but a relatively small part of the interior space of the mail box.

Other objects and attendant advantages of the invention will be apparent to persons familiar with articles of this character from the following detailed description, taken in connection with the accompanying drawings wherein I have illustrated a practical and approved embodiment of the invention, and in which—

Fig. 1 is a front elevation;

Fig. 2 is a side elevation viewed from the left of Fig. 1;

Fig. 3 is a side elevation viewed from the right of Fig. 1;

Fig. 4 is an enlarged vertical section through the box;

Fig. 5 is an enlarged horizontal section taken substantially on the line 5—5 of Fig. 1;

Fig. 6 is a diagram illustrating the lighting circuit of the box lamp from the door bell circuit transformer;

Referring to the drawings, 10 designates as an entirety a substantially rectangular box consisting preferably of a metal casting, the side walls thereof being formed with rectangular openings 11 and 12, one of which is normally closed by a hinged door 13 and the other by a plate 14 secured in place by headed studs 15 which, as shown in Fig. 1, are driven through holes in the side wall of the box above and below the opening 12 with a tight friction fit, but not riveted over, so that the cover plate 14 may be removed by driving out the studs. On the rear edges of the side

walls of the box are cast identical hinge lugs 16 and 17, and on the door 13 are cast cooperating hinge lugs 18. The door 13 is symmetrical, so that it can be applied to the right hand side of the box, if desired, by merely inverting it from the position shown in Figs. 1 and 2, and when so applied to the right hand side of the box, the symmetrical cover plate 14 can be transferred to the left hand side of the box, thus adapting the latter to be mounted adjacent to the vertical door jamb on either side of the door. The door 13 is equipped on its inner side with a box 19 (Fig. 5) containing an ordinary key-operated lock; and mounted centrally on the cover plate 14 is a switch box 20 for making and breaking the circuit to the lamp through a switch-operating lever 21 projecting through the outer cover of the switch box. The front wall of the box is provided with the usual mail delivery chute 22 and hinged cover 23 therefor.

In the front wall of the box is formed an opening 24, preferably obliquely disposed as shown in Fig. 1, said opening formed with a marginal countersunk seat to receive a translucent panel 25 that may be secured in place by an overlying escutcheon frame 26 and fastening screws 27. The translucent panel 25 is designed to have printed, painted or otherwise formed thereon opaque numerals 28 indicating for example a house number.

In the rear of the panel 25 is a light reflecting and diffusing chamber 29 and below and communicating with the latter is a lamp chamber 30; these chambers being preferably formed by inwardly and downwardly extending walls 31 and 32 respectively that are integral with the front wall of the box, the light chamber 30 being further bounded by end walls 33 and 34 located a considerable distance inwardly of the ends of chamber 29 and a bottom wall 35. In a suitable opening in the end wall 33 is mounted a lamp socket 36, which removably supports a small electric lamp bulb 37 substantially centrally of the lamp pocket or chamber 30. The lamp itself is thus positioned below the panel 25, so that the light rays from the lamp extending upwardly from the lighting chamber

30 impinge upon and are reflected by the longitudinally and transversely concave rear wall 31 of the reflecting chamber, for which purposes said rear wall is preferably surfaced with a white enamel or other light reflecting material. By reason of this construction none of the rays of light from the lamp strikes directly against the panel in a direction perpendicular or approximately 5 perpendicular to the latter, but practically all of the rays from the lamp are reflected and diffused within the upper chamber in 10 rear of the panel. The latter is thus subjected to a uniform and diffused light, which 15 enhances the legibility of the numerals on the panel, making them much easier to read than where the light is positioned directly behind the panel so that its rays pass directly through the latter.

20 A light used for such purpose as that above described requires, of course, only a very low voltage current similar to that ordinarily employed to operate a door bell from a house lighting circuit by the aid of a transformer. 25 For this purpose I operate the light circuit from the transformer of the bell circuit, and this is illustrated diagrammatically in Fig. 6 wherein B designates the door bell, P the usual push-button, and BC the bell circuit 30 through the voltage reducing transformer T of the usual house light circuit LC. From one binding post of the transformer T a circuit line 38 extends to and through the switch 20 (Fig. 5) to one terminal of the lamp 35 socket 36, and from the latter a return line 39 is joined at 40 to the return line of the bell circuit BC leading to the other binding post of the transformer. Thus, by a simple manipulation of the switch 21, the lamp 37 40 may be lighted from the usual transformer T of the door bell circuit. This is a convenience in situations where the door bell is operated from the house lighting circuit through a transformer; but, of course, in other situations where the door bell circuit is 45 battery-operated, the mail box lamp may be operated either from the same or an additional battery.

The box is preferably supported on a pair 50 of angle brackets 41, being attached to the upper horizontal limb of the latter as by screws 42, and the brackets themselves being attached to the wall of the house as by screws 43. Integral with the vertical limbs of the 55 brackets 41 are forwardly and upwardly curved arms 44 terminating some distance below the horizontal limbs of the brackets so as to form a simple and convenient rack to support newspapers, packages, and other second-class mail matter too large to be deposited 60 in the box itself.

I claim—

1. A mail box having a translucent panel 65 mounted in its front wall, said front wall being formed with an inwardly and downwardly offset portion, the upper part of which is longitudinally and transversely concave

70 rear of said panel of less depth than the box and a lamp chamber at one side of and communicating with said first named chamber, and a lamp in said lamp chamber located outside the margin of said panel.

2. A mail box having a translucent panel 75 mounted in its front wall, said front wall being formed with an inwardly offset portion forming a light reflecting and diffusing chamber directly behind said panel of less depth than the box and a lamp chamber below and communicating with said first named chamber, and an electric lamp mounted in a wall 80 of said lamp chamber and located behind the portion of said front wall beneath said panel.

3. A mail box having an opening in its 85 front wall, and a translucent panel detachably mounted in said opening; said front wall being formed with an inwardly offset extension the upper portion of which is concave on its front side and forms with said panel a light reflecting and diffusing chamber directly behind said panel of less depth than the box and the lower portion of which forms with the front wall of the box a lamp chamber lying behind the portion of said front wall beneath said panel, and an electric lamp housed in said lamp chamber.

90 4. A mail box having an opening in its front wall, a translucent panel mounted in 95 said opening, a light reflecting and diffusing chamber in rear of said panel and co-extensive lengthwise with the latter, a lamp pocket formed as an offset extension of said chamber of less length than the latter and disposed outside the boundaries of said panel opening, and an electric lamp housed in said lamp pocket.

100 5. A mail box having an opening in its front wall, a translucent panel mounted in 105 said opening, a light reflecting and diffusing chamber in rear of said panel and co-extensive lengthwise and widthwise with the latter, a lamp pocket of less length than said chamber formed as a downwardly offset central 110 extension of the latter and located outside the margin of said panel, and an electric lamp housed in said pocket.

115 6. A mail box having a translucent panel mounted in its front wall, said front wall being formed with an inwardly and downwardly offset portion, the upper part of which is co-extensive with the length of said panel and forms with said panel a light reflecting and diffusing chamber in rear of the latter, and the lower part of which is shorter than 120 said panel and lies below the latter; said shortened portion constituting with the front wall of the box a lamp chamber, and an electric lamp housed in said lamp chamber.

125 7. A mail box having a translucent panel mounted in its front wall, said front wall being formed with an inwardly and downwardly offset portion, the upper part of which is longitudinally and transversely concave

and coextensive with the length of said panel and forms with said panel a light reflecting and diffusing chamber in rear of the latter, and the lower part of which is shorter than
5 said panel and lies below the latter, and constitutes with the front wall of the box a lamp chamber, and an electric lamp housed in said lamp chamber.
